[57] CLAIM

The ornamental design for a type element storage container, substantially as shown and described.

DESCRIPTION

FIG. 1 is a side elevational view of a type element storage container showing my new design;

FIG. 2 is a top plan view thereof;

FIG. 3 is a bottom plan view thereof;

FIG. 4 is an exploded side elevational view thereof with the cover separated from the container; and

FIG. 5 is a cross-sectional view taken along line 5—5 of FIG. 2.

FIG. 1**FIG. 2****FIG. 3****FIG. 4****FIG. 5**
